ROCKET PROJECTILE

William W. Farr, Grosse Pointe, Mich., assignor
by mesne assignments, to United States of
America

Application October 13, 1944, Serial No. 558,582

1 Claim. (Cl. 102—49)

1

This invention relates to rocket projectiles, more particularly to rocket projectiles of the rotational type.

The invention is specifically directed to a type of rocket projectile which includes an elongated casing for containing the propelling charge and having a rearwardly opening discharge passage at its trailing end. In certain devices of this type which have been proposed heretofore, the discharge or Venturi passage for the discharge of the gases resulting from the burning of the combustible propelling charge, was axially arranged at the trailing end of the casing.

One of the objects of the present invention is to provide an improved means associated with the casing in such manner as to provide a plurality of Venturi passages located adjacent the inner wall surface of the casing whereby the gases will have a substantially straight flow toward the Venturi passages.

Another object is to provide a rocket casing with an end closure means which provides with the casing wall, a plurality of circumferentially spaced Venturi passages in which the passages are so disposed as to impart rotation to the rocket projectile.

A further object is to so form the entrance end of the portions of the closure member which form the Venturi passages as to permit smooth flow of the gases into the Venturi passages.

With the above and other objects in view which will be apparent from the following description to those skilled in the art to which the invention appertains, the present invention consists in certain features of construction and combination of parts to be hereinafter described with reference to the accompanying drawing, and then claimed.

In the drawing which illustrates a suitable embodiment of the invention:

Figure 1 is an elevational view of the rocket projectile, portions of the same being in section to show the entire rocket in detail;

Figure 2 is a rear end view of the projectile shown in Figure 1; and,

Figure 3 is a flattened section taken approximately on the circumferential line 3—3 of Figure 2, showing the contour of the portions which form the angularly disposed Venturi passages.

Referring to the accompanying drawing, the 50 rocket projectile of the present invention includes an elongated casing 1 secured at its forward end to the main chambered projectile portion 2 which is arranged to contain the explosive charge (not shown). The propelling charge is 55

2

in the form of annular sticks 3 of combustible material which are supported by a cage member 4. The cage member is supported by a shoulder 5 disposed at the forward end of the casing 1.

The open trailing end of the casing 1 is provided with a cup shaped end closure member 6, the walls of which are radially outwardly offset to provide a plurality of circumferentially spaced projecting portions 7 which are engaged with the inner wall surface of the casing 1. The radial walls 8 and 9 of each portion 7 converge toward each other in a rearward direction as shown in Figure 3. The straight portion of the wall 8 is of lesser length than the wall 9 and is joined to the wall 9 in a sweeping curve 10 whereby to provide a restricted throat 11 between the wall 8 and the longer wall 9 of the next adjacent portion 7, thus forming an elongated Venturi passage. The closure member 6 is rigidly secured to the casing 1 preferably by rivets 12 extending through the casing 1 and the portion 7, there being two such rivets extending through each portion 7 as indicated in the drawing.

25 As will be seen in Figure 3, the portions 7 are so arranged that the axis of each Venturi passage is at an angle with respect to the axis of the casing 1. Due to this angular disposition of the Venturi passages, the gases which result 30 from the burning of the combustible charge sticks 3 flow through the Venturi passages under high pressure, and impart rotation to the projectile. The angular relationship of these passages is such 35 as to give the desired speed of rotation to the projectile.

The closure member 6 may be formed in any suitable manner such as, for example, by die casting or stamping the same from sheet metal.

The element 13 shown at the central portion 40 of the closure member 6 functions to permit the escape of gases in the event excessive pressures are developed in the casing 1. This element however forms no part of the present invention.

The construction described can be economically manufactured and in operation the gases travel in a substantially straight path toward the Venturi passages and enter the passages with a smooth flow.

It is to be understood that various changes may be made in the detailed construction and arrangement of parts without departing from the spirit and substance of the present invention, the scope of which is defined by the appended claim.

What is claimed is:

In a rotational rocket projectile having an elon-

gated casing provided with an open trailing end and arranged to contain a combustible propelling charge, an end closure for said opening and having a plurality of circumferentially spaced radially extending portions engaged with the inner wall surface of said casing, each of said portions having its radial side walls converging rearwardly toward each other, one of said walls of each portion being curved at its forward end toward the other of its walls to provide with the wall of an adjacent portion corresponding to said other wall a restricted throat intermediate the opposite ends of said portions, the inner wall surface of said casing together with the adjacent radial walls of adjacent radially extending portions and the portions of said end closure between and joining said radially extending walls defining a plurality of circumferentially spaced Venturi pas-

sages, the axes of said passages being non-parallel with respect to the axis of said casing, and means for rigidly securing said end closure to said casing.
